UNITED STATES PATENT OFFICE

AUGUSTO DINA, OF ELIZABETH, NEW JERSEY, ASSIGNOR TO INTERNATIONAL PROJECTOR CORPORATION, OF NEW YORK, N. Y., A CORPORATION OF DELAWARE

DESIGN FOR A COMBINATION REEL AND MAGAZINE-FRAME SUPPORT FOR MOTION-PICTURE-PROJECTION MACHINES

Application filed March 31, 1930. Serial No. 35,076. Term of patent 3½ years.

To all whom it may concern:

Be it known that I, AUGUSTO DINA, a citizen of the United States, residing at Elizabeth, New Jersey, have invented a new, original, and ornamental Design for a Combination Reel and Magazine-Frame Support for Motion - Picture - Projection Machines, of which the following is a specification, reference being had to the accompanying drawing, forming part thereof wherein

Fig. 1 is a top plan view of a combination

reel and magazine frame support for a motion picture projection machine, showing the new design;

Fig. 2 is a rear elevational view thereof; and,

Fig. 3 is a side elevational view thereof.

I claim:

The ornamental design for a combination reel and magazine frame support for a motion picture projection machine, as shown.

AUGUSTO DINA.
